(57) **CLAIM**

The ornamental design for a canopy light fixture, as shown and described.

DESCRIPTION

FIG. 1 is a bottom perspective view of a canopy light fixture; FIG. 2 is a top perspective view thereof; FIG. 3 is a front elevational view thereof, the rear elevational view being a mirror image thereof; FIG. 4 is a left side elevational view thereof; FIG. 5 is a right side elevational view thereof; FIG. 6 is a top plan view thereof; and, FIG. 7 is a bottom plan view thereof. The broken lines represent elements which form no part of the claimed design.
